US00D625388S

(12) **United States Design Patent**
Cook

(10) **Patent No.:** **US D625,388 S**
(45) **Date of Patent:** **** Oct. 12, 2010**

(54) **SPRAYER TANK MODULE**

(75) Inventor: **James E. Cook**, Anoka, MN (US)

(73) Assignee: **Pumptec Inc.**, Anoka, MN (US)

(**) Term: **14 Years**

(21) Appl. No.: **29/345,078**

(22) Filed: **Oct. 8, 2009**

(51) **LOC (9) Cl.** **23-01**

(52) **U.S. Cl.** **D23/202**

(58) **Field of Classification Search** **D23/202, D23/203, 225; 220/587, 565, 567.1; 210/532.2**
See application file for complete search history.
